(57) **CLAIM**

The ornamental design for a tri-fold wallet holder for stored value cards, as shown and described.

DESCRIPTION

FIG. 1 is a front perspective view of a first embodiment for a tri-fold wallet holder for stored value cards in a closed position showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a front perspective view thereof in an open position;

FIG. 9 is a front perspective view of a second embodiment for a tri-fold wallet holder for stored value cards in a closed position;

FIG. 10 is a front elevational view thereof in a closed position;

FIG. 11 is a front perspective view thereof in an open position; and,

FIG. 12 is a front perspective view of a first embodiment in an open position with a note card inserted therein.

The tri-fold wallet holders of FIGS. 9-11 have the same top, bottom, first side, and second side views as shown in FIGS. 4-7, respectively.

The broken lines showing in FIGS. 9-11 are included for the purpose of illustrating portions of the tri-fold wallet holder for stored value cards that form no part of the claimed design. The broken lines in FIG. 12 showing a note card are to illustrate environment only and form no part of the claimed design.
